 W. Morris

United States Patent Office.

HENRY W. HARPER, OF BERLINSVILLE, PENNSYLVANIA.

Letters Patent No. 71,609, dated December 3, 1867.

IMPROVEMENT IN MACHINES FOR DRESSING THE FRAMES OF SLATES.

The Schedule referred to in these Letters Patent and making part of the same.

TO ALL WHOM IT MAY CONCERN:

Be it known that I, HENRY W. HARPER, of Berlinsville, Northampton county, Pennsylvania, have invented a Machine for Finishing Slate-Frames; and I do hereby declare the following to be a full, clear, and exact description of the same.

My invention consists of a certain mechanism, fully described hereafter, for planing the upper and lower surfaces of a slate-frame, rounding the edges, and finishing and smoothing the frame, at one operation, with precision and rapidity.

In order to enable others familiar with machinery of this class to make and use my invention, I will now proceed to describe its construction and operation, reference being had to the accompanying drawing, which forms a part of this specification, and in which—

Figure 1 is a sectional elevation of my improved machine for finishing slate-frames.

Figure 2, a plan view, and

Figures 3, 4, and 5 views of parts detached and drawn to an enlarged scale.

Similar letters refer to similar parts throughout the several views.

The side frames A and A' of the machine are connected together by cross-pieces a, and, in suitable bearings secured to the frame, turn three vertical shafts B, C, and D, each of which is furnished with a driving-pulley, b. To the upper end of the shaft B is secured a detachable wheel, F, having upper and lower flanges c and c', between which is a groove, d, (fig. 3.) A cutter, e, similar to that of an ordinary hand-plane, is secured to the upper flange c of the wheel, the cutting-edge projecting a short distance into the groove d; and beneath this cutter, and secured to the flange c', is a similar cutter, e', (see figs. 2 and 3.) A toothed cutter-wheel, G, in which is formed a semicircular groove, f, in line with the groove d of the wheel F, is so secured to the upper end of the shaft C as to be detachable therefrom, the bearings g of this shaft being rendered adjustable, as shown in fig. 4. At the upper end of the third shaft, D, is secured a detachable finishing-wheel, H, having also a groove, g, concave at the end, as shown in the drawing. It will be observed that the grooves of the wheels F, G, and H are in line with each other, and that a table or platform, J, a portion of which is cut out for the reception of each wheel, extends the entire length of the frame of the machine. Guide-plates K (fig. 2) are secured to the table between the wheels F and G and G and H, and two spindles, m and m', turn in the opposite side frames of the machine, and are provided with feed-rollers p p', which project over the table J. The spindle m has a driving-pulley, q, and a pulley, q', for the reception of a band passing round a similar pulley, q', on the spindle m'.

The several shafts being caused to rotate in the direction of their arrows, fig. 2, and the spindles m and m' being turned slowly in the direction of their arrows, fig. 1, the slate-frame (see red lines, fig. 2) in its rough unfinished state is placed upon the table J, and is first passed beneath the feed-pulley p, which moves it forward towards the wheel F, the cutters of which plane the upper and lower surfaces of the frame simultaneously, as shown in fig. 3, thereby reducing it to a uniform thickness. Before the rear end of the slate-frame has passed from between the flanges of the wheel F, it is operated upon by the cutter-wheel G, and its edge is rounded by the same, as shown in fig. 4, the guide-plate K, against which the edge of the frame is maintained, preventing it from being cut away too much. After having been rounded, the slate-frame, still resting against the guide-plate K, is moved forward by the second feed-roller p', and into the groove g of the finishing-wheel H before its rear end has left the cutter-wheel G. After the frame leaves the wheel H, by which its edge is smoothed and finished, the remaining three sides are subjected, one after the other, to the action of the planing, rounding, and finishing-wheels.

The bearings of the shaft C, as before described, are adjustable, so that the cutter G may be moved further from or nearer to the guide-plate K, at pleasure.

The finishing-wheel H may consist of what is termed vulcanite emery; or it may be a plain wheel properly coated with pulverized quartz, glass, or other material for imparting a smooth surface to wood.

It will be evident that, although I have shown the wheels as arranged to revolve in a horizontal plane, the machine may be so arranged that they will turn in a vertical or inclined plane without departing from the main features of my invention. It will also be evident that the faces and edges of slate-frames may be reduced to a uniform finish with rapidity and precision by the above-described mechanism.

I claim as my invention, and desire to secure by Letters Patent—

The combination of the planing-wheel F, cutter-wheel G, finishing-wheel H, and guide-plate K, the whole being constructed and arranged for joint action on the slate-frame, substantially as set forth.

In testimony whereof, I have signed my name to this specification in the presence of two subscribing witnesses.
